DESIGN FOR AN AUTOGRAPHIC REGISTER

Robert Davol Budlong, Chicago, Ill., assignor to United Autographic Register Co., Chicago, Ill., a corporation of Illinois

Application January 24, 1936, Serial No. 60,794

Term of patent 7 years

To all whom it may concern:

Be it known that I, Robert Davol Budlong, a citizen of the United States, residing at Chicago, county of Cook, and State of Illinois, have invented a new, original, and ornamental Design for an Autographic Register, of which the following is a specification, reference being had to the accompanying drawing, forming a part thereof, in which:

ister embodying the invention; Fig. 2, a side elevational view of the same; Fig. 3, an end elevational view of the delivery end of the register; and Fig. 4, an end elevational view of the opposite end of the register.

I claim:

The ornamental design for an autographic register, as shown.

ROBERT DAVOL BUDLONG.
